EXHAUST GAS PURIFYING METHOD AND APPARATUS
James B. Campbell, Glendale, Calif.
(755 Walnut St., Gadsden, Ala.)
Filed Jan. 5, 1960, Ser. No. 619
1 Claim. (Cl. 60—38)

This invention relates to novel and improved apparatus and method for reducing the noxious content of exhaust gases, both gaseous and solid, ordinarily discharged into the atmosphere by internal combustion engines and other apparatus producing such exhaust gases.

The primary object of the invention is the provision of efficient, simple, and easily used and operated means of the character indicated, which produces continuous and more complete combustion of exhaust gases by injecting oxygen-bearing atmospheric air under pressure into an exhaust conduit, at a location close to the origin of the exhaust gas, as close to the exhaust ports of an internal combustion engine within its exhaust manifold, and at the exhaust gas flame points therein, so as to relieve oxygen starvation at these points and supply oxygen thereto, in a manner to effect more complete combustion of components of the exhaust gas which otherwise contaminate the atmosphere when discharged thereinto.

Another object of the invention is to provide apparatus of the character indicated above which is readily adaptable to and is easily installed on different forms and sizes of internal combustion engines, and in particular the engines of vehicles, and which can be produced at sufficiently low cost to warrant widespread use thereof on vehicles, in the interest of the reduction of "smog" and air pollution.

A further object of the invention is to provide apparatus of the character indicated above which involves no fire hazards, operates only while the associated engine is in operation, involves no electrical consumption or control problems, and provides for the burning of the noxious exhaust gas components, both gaseous and solid, and consequent increases in exhaust gas temperature, in a fully enclosed, protected, and readily controlled portion of an exhaust system, together with cooling of the purified exhaust gas before its discharge into the atmosphere.

Other important objects and advantageous features of the invention will be apparent from the following description and the accompanying drawings, wherein, for purposes of illustration only, a specific form of the invention is set forth in detail.

In the drawings:

FIGURE 1 is a fragmentary and contracted schematic view showing apparatus of the invention installed in a vehicle internal combustion engine exhaust system;

FIGURE 2 is an enlarged longitudinal section taken through the air compressor shown in FIGURE 1;

FIGURE 3 is a transverse section taken on the line 3—3 of FIGURE 2;

FIGURE 4 is an enlarged longitudinal section taken through the back-pressure valve of FIGURE 1, showing the valve element in closed position;

FIGURE 5 is a fragmentary perspective view of a compressor rotor;

FIGURES 6 and 7 are transverse sections taken on the lines 6—6 and 7—7, respectively, of FIGURE 2;

2

FIGURE 8 is an enlarged fragmentary vertical longitudinal section, with portions broken away, taken through the engine exhaust manifold and its exhaust pipe;

FIGURE 9 is a vertical transverse section taken on the line 9—9 of FIGURE 8;

FIGURE 10 is a horizontal section taken on the line 10—10 of FIGURE 8; and

FIGURES 11 and 12 are horizontal sections taken on the lines 11—11 and 12—12, respectively, of FIGURE 8.

Referring in detail to the drawings, wherein like numerals designate like parts throughout the several views, the numeral 10 designates a vehicle internal combustion engine block having longitudinally spaced lateral exhaust ports 12 opening therefrom, which communicate with a horizontal exhaust manifold 14. At a suitable point between two adjacent exhaust ports 12, as at the middle thereof, the exhaust manifold 14 is formed with a vertical tubular exhaust pipe junction 16 to the lower end of which downwardly extending exhaust pipe 18 is fixed. The junction 16 has a closed top wall 20 which is preferably on a level slightly above the top wall of the manifold 14, as shown in FIGURES 8 and 9.

Extending downwardly in and concentrically spaced from the side wall 22 of the junction 16 is a diffuser assembly 24, which comprises an outer vertical cylindrical tube 26, of uniform diameter, having an imperforate upper side wall portion 28 extending above the junction top wall 20, and a perforated lower side wall portion 30 extending below the top wall 20. The perforations 32 of the lower side wall portion 30 are evenly distributed and are relatively large in size. The imperforate upper side wall portion 28 is threaded, at its lower end, as indicated at 34, in a central opening 36 provided in the junction top wall 20, and a nut 38 fixed on the portion 28 above the threads 34, bears upon a gasket 40 which is engaged with the upper surface of the junction top wall 20.

Above the nut 38 the upper side wall 28 of the tube 26 is externally threaded, as indicated at 42, to connect thereto the lower end of a coupling sleeve 44, whose upper end is threaded, as indicated at 46, onto the lower end of the downwardly extending arm 48 of an elbow 50, whose horizontal arm 52 merges into the adjacent end of a preferably horizontal air pipe 54, to whose other end an air compressor 56 is connected.

The diffuser assembly 24 further comprises a vertical inner tube 58, which is somewhat shorter than the outer tube 26 and which is concentrically spaced therein. The inner tube 58 is uniform in diameter and has a perforated lower portion 60 and an imperforate upper portion 62. The perforations 64 of the lower portion 60 are uniformly distributed therein, are of substantially the same size as the outer tube perforations 32, with some of the inner tube perforations 64 registered with perforations of the outer tube 26, as shown in FIGURE 9. The inner tube 58 is spaced from the outer tube 26 by means of circumferentially spaced lugs 59 located in the region of the nut 38, as shown in FIGURES 9 and 10.

The inner tube 58 terminates at its lower end, at a point near to and spaced upwardly from the lower end 66 of the outer tube 26, in a downward flare 68 which is imperforate and is connected at its lower end to the lower end 66 of the outer tube 26. The inner tube 58 extends above the upper end 70 of the outer tube 26 and

well into the vertical arm 48 of the elbow 50, where the tube 58 terminates in an upward flare 72, which is concentrically spaced in the arm 48, and which produces some venturi acceleration of air down through the inner tube 58.

In operation, part of the air under pressure in the air pipe 54 and moving toward the diffuser assembly 24, passes downwardly through the upper flare 72 and into the inner diffuser tube 58, whence the air passes laterally outwardly through the inner tube perforations 64 into the space between the inner tube 58 and the outer tube 26, and outwardly through perforations 32 of the outer tube 26, into the interior of the junction 16. Another part of the air under pressure in the pipe 54 passes downwardly in the space between the inner tube 58 and the outer tube 26 and is discharged laterally from the outer tube 26 through its perforations 32, along with air from the perforations 64 of the inner tube 58, into the interior of the junction 16, this ejection of streams or jets of air into the junction 16 from the outer tube perforations 32 being accelerated by the pressures of the jets of air emerging from the perforations 64 of the inner tube 58.

The interior of the junction 16 constitutes an engine exhaust gas flame point, whereat partially ignited and unburned noxious products of combustion, both gaseous and solid, escaping from the cylinders of the engine block 10 into the exhaust manifold 14, are present in highest concentration and at maximum temperature in the exhaust system. The partially ignited and unburned condition of these products, being due mainly to their being partially deprived or starved of oxygen in amounts sufficient to enable their complete combustion, the forced turbulent entry of oxygen bearing air into the exhaust system at the flame point, produced by the diffuser assembly 24, effects substantially complete burning out or combustion of these products, so that these products are not discharged into the atmosphere through the exhaust pipe 18.

Further, the downward flow of air under pressure from the air pipe 54 through the inner diffuser tube 58 and out of the flare 68 at its lower end, has the effect reducing the turbulence of the flow of the air injected exhaust gases in the junction 16 and in the exhaust pipe 18 immediately below the diffuser assembly 24, and to cool the same, to the extent that exhaust gases traveling through the exhaust pipe 18, to discharge into the atmosphere, are not objectionably higher in temperature than normal.

The air pressure pipe 54 has connected therein, at a point intermediate its ends, as shown in FIGURES 1 and 4, a back-pressure valve 76, which can comprise a tubular valve body 78 which is sleeved on the adjacent spaced ends 80 and 82 of sections of the air pipe 54, and a flat plate valve element 84, which is hinged, at 86, on the body 78 so as to abut and close the pipe section end 82, as shown in full lines in FIGURE 4, only when there is back-pressure in the pipe 54, as when the associated engine is being started. Normally, air pressure in the pipe 54, produced by operation of the compressor 56, holds the valve element 84 in its open position, indicated in phantom lines in FIGURE 4.

The compressor 56 comprises an elongated open-ended cylinder 88, of uniform diameter, having external laterally annular flanges 90 and 92, on its forward and rear ends, respectively. A forwardly tapered reducer 94 has a lateral annular flange 96 on its rear end which is registered with and secured to the forward cylinder flange 90, as by means of studs 98, and a neck 100 on the forward end of the reducer 94 has the related end of the air pipe 54 connected thereto.

At its forward end, the cylinder 88 has an internal annular stop rib 102, which is engaged by the forward end 104 of a stator tube 106 which is removably inserted forwardly in the cylinder 88 through its rear end. The stator tube 106 has a rear end 108 with which is abutted an inner edge portion 110 of a ring 112 which is removably

secured to the rear cylinder flange, as by means of studs 114.

As shown in FIGURES 2, 6 and 7, the stop rib 102 and the ring 112 have spiders therein which are composed of radial arms 116 and 118 meeting enlarged cross section, rearwardly extending hubs 120 and 122, respectively. The hubs 120 and 122 have axial bores 124 and 126, respectively, which extend therethrough, to journal the forward end portion 128 and an intermediate 130 of a rotary impeller shaft 132, the shaft 132 having on its rear end drive means, such as a pulley 134, to be drivingly connected to drive means (not shown) such as a motor or a rotary component of the associated engine.

The stator tube 106 has fixed on the interior thereof, at uniformly spaced intervals therealong, and at uniformly circumferentially spaced intervals therearound, flat radial stator blades 136, having rounded inner ends 138 which are spaced from the rotor shaft 132, the stator blades 136 being all angled at forty-five degrees to the axis of the shaft 132, five stator blades 136 being shown.

Circumposed on the rotor shaft 132, and splined thereon, as indicated at 140, is a sleeve 142, whose forward end abuts the forward hub 120, and whose rear end abuts the forward side of the rear hub 122. Fixed on the exterior of the sleeve 142 are flat radial rotor blades 144, the same in number as the stator blades 136, which are similar to the stator blades 136 and are disposed in the spaces between the stator blades, and are angled at forty-five degrees to the shaft 132, oppositely to the angulation of the stator blades 136, as shown in FIGURE 5, the stator blades 136 being rearwardly angled and the rotor blades 144 being forwardly angled, so that atmospheric air is drawn through the open rear end of the compressor cylinder 88 and driven through the reducer 94, and accelerated thereby, into the air tube 54, and through the diffuser assembly 24, when the rotor shaft 132 is rotated by its drive means, only while the associated engine is operating.

As enabled by the above described apparatus, as being one suitable form of apparatus, the method of the invention comprises injecting and diffusing air under pressure into the exhaust gas flame point of an internal combustion exhaust system, whether of an engine or of another device, in a manner to forcibly supply oxygen to the exhaust gases at the flame point, sufficient to produce substantially complete combustion or burning out, at the flame point, of those exhaust gas components, both gaseous and solid, which ordinarily pass the flame point and are discharged from the exhaust system into the atmosphere, and which are noxious and pollute the atmosphere.

Although there has been shown and described herein a preferred form of the invention, it is to be understood that the invention is not necessarily confined thereto, and that any change or changes in the structure of and in the relative arrangements of components thereof are contemplated as being within the scope of the invention as defined by the claim appended hereto.

What is claimed is:

An exhaust gas system comprising a horizontal internal combustion engine manifold, a vertical tubular junction connected in communication with the manifold and spaced from its ends, said junction having a top wall and having an open lower end for connection to a muffler equipped exhaust pipe, a vertical tubular diffuser smaller in diameter than and concentrically spaced within the junction, said diffuser being supportably engaged through the top wall of the junction, said diffuser having an upper end above said top wall adapted to be connected to a source of air under pressure, said diffuser comprising concentrically spaced outer and inner tubes, said tubes having coextensive portions formed with closely spaced perforations extending for the major part of their lengths and girths, imperforate means spacing and connecting the tubes at their lower ends and closing the lower end of the space between the tubes, said outer tube terminating at its upper end in the region of said top wall, said inner tube having

an imperforate upper end portion rising above the top wall and communicating at its upper end with said source, the space between the outer and inner tubes at the upper end of the outer tube being in communication with said source.
